(57) **CLAIM**

The ornamental design for a link pin for conveyor chain, as shown and described.

DESCRIPTION

FIG. 1 is a front elevational view of a link pin for conveyor chain in accordance with our new design, the rear elevational view being an identical view thereof;

FIG. 2 is a top plan view thereof, the bottom plan view being an identical view thereof;

FIG. 3 is a side elevational view thereof, the other side being an identical view thereof; and,

FIG. 4 is a front perspective view thereof.

1 Claim, 2 Drawing Sheets

FIG. 2

FIG. 1
